Eugene A. Reilly,

by Edison Brittnys.

UNITED STATES PATENT OFFICE.

EUGENE A. REILLY AND ROBERT M. McLAIN, OF FORT WORTH, TEXAS.

APPARATUS FOR CRACKING AND REFINING OIL.

Application filed October 19, 1921. Serial No. 508,825.

To all whom it may concern:

Be it known that we, EUGENE A. REILLY and ROBERT M. McLAIN, citizens of the United States, residing at Fort Worth, 5 in the county of Tarrant and State of Texas, have invented certain new and useful Improvements in Apparatus for Cracking and Refining Oil, of which the following is a specification.

10 This invention relates to an apparatus for cracking and refining mineral oil under pressure in pipes and in a still, in which pressure is produced by a pump and circulating pipes instead of by vapors.

15 The object of our invention is to provide for simplifying the cracking process for refining oil by operating under pressure of a pump through a series of circulating pipes instead of pressure produced by vapors 20 alone in a still chamber.

Another object is to provide a simple, compact and effective apparatus which can be economically operated for producing gasoline or other low boiling point oils from 25 relatively high boiling point oils.

The matter constituting our invention will be defined in the claims.

We will now describe the details of construction of one embodiment of apparatus 30 adapted for carrying out our process, by reference to the accompanying drawing, which represents a longitudinal sectional elevation of the apparatus.

In our apparatus we preferably use a 35 cylindrical still 1 made of boiler iron set in walls X, and having a dome 2, with which connects a vapor outlet pipe 3, having a valve 4. The outlet pipe may connect with a well known condenser, not here shown. 40 The valve 4 may be adjusted to place the contents of the still chamber 1^a under any desired pressure, but we do not depend on vapors alone to produce pressure on the oil in the still, or in the pipes located partly 45 in the still. The pressure will be produced by a pump or equivalent means for forcing the oil under pressure into pipes 8, 8^a as described below. An oil inlet pipe 5, having a valve 5^a, connects with the still, 50 and a body of oil is preferably maintained in the latter up to the line w. An outlet pipe 6, having a valve 6^a, (a suction line) leads from the still, at a suitable height above the bottom, and connects with a high 55 pressure pump 7. The discharge pipe-line 8 leads from the pump and is preferably 30 pounds or more, is maintained in said

connected in lengths by return-bend couplers a or elbows, to form a serpentine coil in a furnace or heating chamber W below the still 1. The chamber may be heated by 60 gas or oil burners 16 or by other fuel. The coil 8 enters the lower part of the still at a' and is continued as a serpentine coil 8^a to the union coupler b where it connects with a jet or spray nozzle 9, having a contracted passage 10, like a Venturi tube, and provided with a valve seat 10^a. The outer surface of the nozzle 9 may be screw threaded. Above the nozzle is secured a pendent valve housing 12 having a downward extension 12^a adapted to fit over the nozzle and be secured thereto by a threaded connection. The extension may, however, be simply slid over the nozzle. If a screw threaded connection is used the housing 12 75 will serve to hold the nozzle with its seat 10^a in the desired position with reference to the needle valve 15. The housing 12 is also provided with a spray chamber 12^b having openings 11 for discharging vapor 80 and oil spray into the still chamber 1^a. The housing 12 is preferably secured by bolts c directly to the top of the still, but may be otherwise supported in place within the still chamber 1^a. A complementary part 85 13 of the valve housing, which may be a casting, is also secured by the bolts c to the top plate of the still and is provided with a pivot post or standard 13^a. The parts 12 and 13 have registering central 90 openings 11^a for the needle valve 15 and the part 13 has a stuffing box e for said valve.

The post 13^a may be slotted and have pivotally connected to it by a pin g, the 95 weighted lever 14, carrying an adjustable weight d. Near the post 13^a is pivotally connected by a pin f, the needle valve 15, having a point 15^a adapted to close on the seat 10^a and thus control the pressure in the coil 100 8-8^a.

The heating coil 8 may be located in a heating chamber detached from the still 1 so that said coil may be independently heated to any desired temperature without too 105 highly heating the bottom of the still and causing deposit of carbon thereon.

The high pressure pump 7 is adapted to maintain a pressure in the discharge line and coils or conduits 8, 8^a of 30 pounds, and 110 in practice a suitable pressure, preferably 30 pounds or more, is maintained in said

conduits. The weight on the lever of the needle valve 15 will be adjusted to maintain the desired pressure in the conduits and to pop off at or above 30 pounds pressure. The heated oil and vapor will be expelled through nozzle 9 and will hit with great force the wall of the spray chamber 12^b and thus be dashed into spray, and the distillate and cracked vapor will pass into the space above the body of oil and thence off through pipe 3 to a condenser. Oil will be supplied to the still 1 through pipe 5 till a sufficient body thereof is formed, which may be up to or near the line *w*. The coils or conduits 8, 8^a and the still are suitably heated by oil or gas burners 16 or other fuel and then the pump 7 is started to circulate oil through the system. The oil passing through the coil 8^a serves to heat the body of oil in the still. Any heavy oil which is forced out of the nozzle 9 and not properly vaporized will fall back into the body of oil in the still to be again forced or circulated through the system. Any solid matter, as carbon, which is forced out through the nozzle 9 will fall into the bottom of the still chamber and may be drawn off when cleaning the still. Residual oil may be drawn off from the still at suitable intervals by a stopcock 17 having a valve *n*. In practice the still will be provided with the necessary manholes and covers.

The operation of the apparatus is very simple and can be carried out by a few laborers.

Having described our invention, what we claim and desire to secure by Letters Patent, is:

1. Apparatus for distilling and cracking oil, comprising a still, a conduit for liquid outside of the still, means for supplying oil under pressure to said conduit, means for heating said conduit, a conduit in the still connecting with the outside conduit, for heating a body of oil in the still, and a spraying device connecting with the inner conduit in the upper part of the still, whereby oil may be forced under pressure, heated and serve

for heating a body of oil in the still and then sprayed in contact with such body of oil.

2. Apparatus for distilling and cracking oil, comprising a still, a conduit therein for oil, a spray chamber in said still having openings communicating with said still, a spray on the end of said conduit and projecting into said spray chamber, said spray chamber having walls adjacent said spray, and means for forcing hot oil under high pressure through said spray and against the walls of said spray chamber.

3. Apparatus for distilling and cracking oil, comprising a still, a conduit therein for oil, a spray chamber in said still having openings communicating with said still, a spray on the end of said conduit and projecting into said spray chamber, an automatically regulated needle valve controlling said spray, said spray chamber having walls adjacent said spray, and means for forcing hot oil under high pressure through said spray and against the walls of said spray chamber.

4. Apparatus for distilling and cracking oil, comprising a still, a conduit therein terminating in a spray nozzle, having a valve seat, an automatic pressure valve adapted to rest on said seat, and means for forcing oil under pressure through said conduit, and spray nozzle.

5. Apparatus for distilling and cracking oil, comprising a still, a conduit therein, a spray nozzle connecting to the end of said conduit and having a valve seat, a housing for a needle valve secured above the nozzle near the top of the still, a needle valve in the housing and adapted to close on said seat and means for holding it under pressure on its seat for causing a working pressure in the coil and still.

In testimony whereof we affix our signatures.

EUGENE A. REILLY.
ROBERT M. McLAIN.
